UNITED STATES PATENT OFFICE.

GUSTAVE SIEBERT, OF ST. PAUL, MINNESOTA.

TROUSER SUPPORT.

Application filed July 2, 1923, Serial No. 649,109. Renewed December 1, 1926.

My invention relates to trouser supports and has for its object to provide a support for trousers which is fully concealed beneath the apparel of the wearer and which 5 serves to support the trousers from six points or more so that the trouser hangs perfectly even and uniform without sagging at any point.

Another object resides in providing a device 10 adapted to hold portions of the trouser waist band outstretched so that the same is prevented from coming together and bagging.

In carrying out the objects of my invention, I employ a number of supporting members which are adapted to be attached to the suspender buttons of the trousers and which extend across between the same to hold the buttons properly spaced so that the portions 20 of the trouser to which they are attached will not come together to cause the trouser waist band to bag. In addition, I form said supports with a loop or eye positioned midway between the button to which a hook secured to the suspender proper may be attached, which suspender hook is adapted to be concealed beneath the apparel of the wearer.

The full objects and advantages of my invention 30 will be found in the detailed description of the same and are particularly pointed out in the claim.

In the drawings representing my invention in one form:

Figure 1 is a perspective view of a pair 35 of trousers having my invention attached thereto.

Figure 2 is a perspective view of the supporting members forming a portion of my 40 invention.

Figure 3 is a perspective view of the hook member used in conjunction with my invention.

Figure 4 is an elevational view of a portion 45 of the pair of trousers shown in Figure 1 drawn to an enlarged scale, including a pair of suspender buttons, having my supporting member attached thereto.

Figure 5 is a vertical sectional view taken 50 through the center of the supporting member when the suspenders have been attached to the supports.

In the supporting of trousers by suspenders, considerable difficulty has been found in 55 that the trousers between the suspender buttons come together giving a baggy appear-

ance when the trousers are worn without a belt. In addition, the forward portion of the trousers tends to sag when the ordinary suspenders are used giving an unsightly appearance. My invention overcomes these objections by providing supporting members which are fastened in between pairs of suspender buttons to which the suspenders are attached which serve to hold the trousers 60 supported in a neat and uniform manner.

In Figure 1, I have shown a pair of trousers 10 having a waist band 11 to which the usual suspender buttons 12, 13, 14, 15, 16 and 17 are attached on the interior of the same. 70 To each pair of suspender buttons is attached a rigid supporting member A which extends across the interior of the waist band 11 within the same and holds the portion of the trousers between the buttons properly 75 spaced. I have shown at B a pair of suspenders which has a rear band 18 and front bands 19 and 20 which are adapted to be secured to the supporting members A at the centers thereof and which pass over the 80 shoulders of the wearer in the usual manner.

The construction of the supports A can best be seen in Figure 2. These devices are preferably made of wire and consist of a body portion 21 being formed at its center 85 with a loop or eye 22 and at its ends with hooked portions 23 and 24.

In applying the device, the supports A are attached to the trousers by means of the hooked portions 23 and 24 which are hooked 90 over the suspender buttons 12 and 13, as illustrated in Figure 4 with the loop 22 extending upwardly. When so positioned, the supports A lie flat against the interior of the waist band 11, being inconspicuous and 95 out of the way. When the suspenders are removed, as will be presently explained, the said supports A are left in place upon the trousers.

To the ends of the suspender bands 18, 19 and 20, are attached fasteners C which may be attached to the supports A to hold the trousers in place. These fasteners are also made of wire and consist primarily of a hook 25 which is connected by side members 100 26 and 27 to a shank 28. The shank 28 is directly connected to the end of the respective suspender straps 18, 19 and 20 in the customary manner, while the hooks 25 are adapted to be hooked into the loop 22 of 110 the supports A.

In using the invention, the supporting

members A are first attached to requisite suspender buttons of the trousers, as shown in Figures 1 and 4. The suspenders B are then placed over the shoulders of the wearer and the shirt of the wearer put on. The trousers having the supporting members A therein are next put on whereupon the hooks 25 of the fasteners C may be hooked into the loops 22 of the supporting members A through the shirt proper to support the trousers through the supporting members A from the suspenders B.

With my invention, the trousers lie perfectly flat along the person of the wearer without bagging or drooping at any portion of the same. The suspenders and the supporting means are completely concealed and the suspenders may be quickly and easily removed when desired.

In accordance with the patent statutes, I have described the principles of operation of my invention, together with the appara-

tus which I now consider to represent the best embodiment thereof, but I desire to have it understood that the construction 25 shown is only illustrative and that the invention can be carried out by other means and applied to uses other than those set forth within the scope of the following claim.

30

I claim:

In combination with a pair of trousers and the suspender buttons thereof positioned beneath the waist of said trousers, a straight rigid member having a loop with 35 an open flaring mouth therein positioned at approximately the central portion of said member, hooks formed upon the ends of said member in the same plane as said loop adapted to engage said suspender buttons 40 and another hook to engage the loop formed at the central portion of said member.

GUSTAVE SIEBERT.
